Primary Examiner — Cynthia M Chin(74) *Attorney, Agent, or Firm* — Fulwider Patton LLP(57) **CLAIM**

The ornamental design for a toy house, as shown and described.

DESCRIPTION

FIG. 1 is a front perspective view of a toy house unit showing my new design;

FIG. 2 is a rear perspective view thereof;

FIG. 3 is a front elevational view thereof;

FIG. 4 is a right elevational view thereof;

FIG. 5 is a top plan elevational view thereof;

FIG. 6 is a right side elevational view thereof; and,

FIG. 7 is a left side elevational view thereof.

The bottom of the toy house design is flat and devoid of surface ornamentation.

The features shown in broken lines with consistent dash lengths illustrate toy house unit ornamentation, features, and/or environment that form no part of the claimed design.
